CLAIM

The ornamental design for a terminal, as shown and described.

DESCRIPTION

FIG. 1 is a top, front, and left side perspective view of a terminal showing the new design.

FIG. 2 is a top, rear, and right side perspective view of the terminal showing the new design.

FIG. 3 is a bottom, rear, and left side perspective view of the terminal showing the new design.

FIG. 4 is a front view of the terminal showing the new design.

FIG. 5 is a rear view of the terminal showing the new design.

FIG. 6 is a left side view of the terminal showing the new design, (the right side view being a mirror image thereof).

FIG. 7 is a top view of the terminal showing the new design; and,

FIG. 8 is a bottom view of the terminal showing the new design.

The broken lines show unclaimed portions of the terminal and form no part of the claimed design, and the surface shading lines indicate contour or curvature of the surfaces.
